UNITED STATES PATENT OFFICE.

FRANCIS CHARLES ZACHARIE, OF NEW ORLEANS, LOUISIANA.

WATER-CLOSET.

SPECIFICATION forming part of Letters Patent No. 768,890, dated August 30, 1904.

Application filed April 27, 1904. Serial No. 205,172. (No model.)

To all whom it may concern:

Be it known that I, FRANCIS CHARLES ZACHARIE, a citizen of the United States, residing at New Orleans, Orleans parish, Louisiana, have 5 invented certain new and useful Improvements in Water-Closets, of which the following is a specification.

My invention relates to water-closets of that class in which a flushing apparatus is used for 10 cleansing the bowl. It is applicable to such closets whether the valve be automatically, intermittent in its action or whether the valve be such that the water flows while the valve is held open.

15 The object of the invention is primarily to hold up the seat when not in use, so that the bowl may be used also as a urinal; but it also includes a construction whereby the lowering of the seat to its place upon the bowl operates 20 the valve to flush the bowl.

My invention is illustrated in the accompanying drawings, in which—

Figure 1 shows the seat in an elevated position, together with its connections in position corresponding thereto. Fig. 2 is a like 25 view of the seat closed and the connections with the valve under tension.

In the drawings, T represents a flushing-tank of any suitable construction having a 30 flushing-valve. The special form of valve-operating arm is shown at A, by the downward pulling of which the flushing-valve is operated. This is representative of any form of valve-operating connection. To this arm is 35 connected a chain F, which runs over a pulley B, fixed to a suitable support. From this pulley a chain extends downwardly and is connected to a second chain E, attached by any suitable means, such as a bracket G, to the 40 seat S. This chain E extends upward and runs over a pulley C, suitably supported on the tank, whence it extends downward, where its free end is connected with a weight D. This weight is sufficient to counterbalance the 45 weight of the seat and to raise and hold it in the position shown in Fig. 1. I prefer to make this weight D in the form of a hollow

ball with an opening, so that it may be filled with sand or other weighty substance and accurately adjusted, so as just to overcome the 50 weight of the seat. The parts are so adjusted that when the seat is pressed down it will pull upon the chain E, raise the weight, and also pull sufficiently upon the chain F to operate the valve-arm A. The chain shown is representative of cord or any suitable connection. 55 The seat is pivoted in the ordinary manner, and the chain connections therewith are adjusted upon the seat into proper position to allow the seat to rise and fall with sufficient 60 scope for the operation of the valve.

The advantages incident to the use of this invention will be obvious, but may be briefly stated, as follows: While in use by a person sitting on the seat the bowl of the closet is 65 flushed from the tank with water, so as to carry off the fecal matter as fast as dropped, and thus allowing little or no escape of the odor and stench. The matter being thus carried off, none remains in the bowl when the person 70 rises from the sitting posture, and there is no necessity of pulling the chain or cord to empty the bowl as in the ordinary closet, a thing which is often neglected, whereby a considerable nuisance is created. Further, when 75 the closet is not in use by a person sitting on it the seat of the closet is raised by the weight and the bowl of the closet can be made use of as a urinal, whereas in the ordinary closet, the seat-lid being down, careless persons 80 wet the seat by urinating thereon. Again, the device will thus do away with the necessity of a urinal separate and distinct from the closet, thus avoiding the additional expense of the urinal, and it can be applied to any 85 closet having a flushing-tank, and, finally, it is purely automatic and obviates all the evil effects of persons using the ordinary closet in a careless or negligent manner.

I claim as my invention—

1. In combination, the bowl, a hinged seat, an overhead flushing-tank, a chain connecting the seat with the valve of the overhead tank for operating the same, and a weight connect-

ed with said chain and arranged to normally hold the seat in a practically vertical position, substantially as described.

2. In combination with a bowl and its hinged seat, and with the valve of the flushing-tank, a chain E running over a pulley C and having on its free end a weight D, and a chain F connected with the valve-operating arm and run-

ning over a pulley B into connection with a chain E, all substantially as described. ¹⁰

In testimony whereof I affix my signature in presence of two witnesses.

FRANCIS CHARLES ZACHARIE.
